SIGN HOLDER

Filed May 23, 1932

UNITED STATES PATENT OFFICE

ROBERT W. SCHWAB, OF ATLANTA, GEORGIA, ASSIGNOR TO SOUTHERN SPRING BED COMPANY, OF ATLANTA, GEORGIA, A CORPORATION OF GEORGIA

SIGN HOLDER

Application filed May 23, 1932. Serial No. 613,026.

The present invention relates to sign holders or stands for the display of advertising cards or the like and particularly to the type of card holder or card display device which is designed and intended to stand erect upon a floor or sidewalk.

Many types of such display card holding devices have heretofore been designed or suggested and put into use, but the present invention contemplates an improved article of manufacture of this class, by means of which a card may be firmly supported in the desired position and which is at the same time ornamental in appearance, simple and inexpensive to construct, and light in weight, without at the same time being unstable. In fact, a sign holder constructed in accordance with the present invention has a maximum of stability for a minimum weight. The various elements which go into its construction are of simple design, the assembly of these elements may be accomplished with great rapidity and small expense, and the display cards are furthermore so supported in position that removal and replacement of one display card by another may be easily effected without disassembling any of the major parts of the holder.

A preferred embodiment of the holder is disclosed in the accompanying drawing, in which:

Figure 1 is a perspective view of the holder showing a display card positioned therein;

Figure 2 is a section on the line 2—2 of Figure 1, to a larger scale and partly broken away; and

Figure 3 is a section on line 3—3 of Figure 1.

Essentially the sign holder includes a base and a card holding frame, the frame being rigidly secured to the base and preferably comprising the means for securing the separated portions of the base together.

The base comprises spaced parallel members 10 similar in form and construction. Each of these members 10 is fabricated of a metallic channel member, the end portions of which are curved downwardly, as shown, so

that the end surfaces comprise floor engaging surfaces, the main or central portions of said members being horizontally disposed. Base members so constructed are attractive in appearance, efficient in use as sign supporting members, and may be easily and cheaply fabricated.

The card supporting portion of the display stand comprises two vertically disposed one-piece members 11, each fabricated of a narrow band or strip of metal and each having the form of an inverted U, the stems or legs of which are parallel and closely spaced, the inner surfaces of these stems defining between them elongated slots. The lower ends of the stems or legs are turned outwardly to provide flange-like portions 11' which are secured, respectively, to the base members 10 by any suitable means, as by welding, riveting, or by bolts such as indicated at 12.

Cross tying and sign supporting elements are indicated at 13, these elements being parallel and substantially horizontally disposed, and the ends of each element being positioned within the slots defined by the stems of members 11, one element having its ends received within the tops of these slots and the other within the bottoms of the slots. Elements 13 are preferably channel-like in cross-section, having mutually facing grooves which are adapted to receive and retain the parallel upper and lower edges of a display card or sign indicated at 14. Advantageously elements 13 are substantially U-shaped in cross section, and it is highly desirable to have the upper element 13 in the form of an inverted U so that the outside surfaces of its ends may fit closely against the inside surfaces of the upper ends of the slots defined by the members 11. Elements 13 may be rigidly secured to members 11 in any suitable manner, and I have found that a very strong and rigid construction is realized when elements 13 are welded to members 11. In the drawing two of these welds are indicated at 15, 15.

The card 14 is adapted to be inserted laterally through the slot defined by one member 11, the lower edge of this card resting within the groove in the lower element 13 and the upper edge within the groove defined by the upper 100

per element 13. The four edges of the card are thus hidden from view and well supported by the frame. Preferably I provide limiting stops 16, 16 in one of the slots to limit movement of the card in one direction, the cards being inserted through the opposite slot and moved into contact with these stops. In addition to stops 16, I preferably employ a member 17, such, for instance, as a cotter pin, which is adapted to be passed through 5 registering apertures 18 formed in the stems or legs of the opposite supporting member 11. This pin or locking device (which may be of any type) is placed in the operative position 10 shown after a card has been inserted, and the effect is to lock the card in position. It may be readily removed, however, whenever it is desired to remove one display card or advertisement and replace it by another. 15

20 A sign holder constructed in accordance with the present invention is seen to comprise only six principal parts, i. e., two base members, two vertical members, and two cross tying and card supporting members. These parts are fabricated from commercial stock 25 with a minimum of cutting and shaping operations and may be easily secured together into one solid integral structure. The resulting stand or holder is pleasing to the eye, 30 sturdy, and may be constructed at minimum cost for an article of this character. 35

Having thus described the invention, what is claimed as new and desired to be secured by Letters Patent is:

- 35 1. As an article of manufacture, a sign holder of the type described including, in combination, spaced base members having floor engaging portions and a frame affixed thereto for supporting a flat display card in such manner that it may be readily removed, 40 said frame having two vertically disposed one-piece members each having the form of an inverted U, the stems or legs of which define between them a narrow vertical slot, the bottoms of said stems having substantially 45 horizontal portions projecting outwardly and secured to said base members, and two cross tying and sign supporting elements disposed substantially horizontally, one such element 50 having its ends positioned within the slots of said members at the tops thereof and the other having its ends positioned within said slots at the bottoms thereof, the said ends of the elements being rigidly secured to said members 55 and said elements having mutually facing continuous grooves formed therein and adapted to receive and retain, respectively, the upper and lower edges of a display card inserted laterally into said frame through one 60 of said slots. 65
2. The combination set forth in claim 1 in which the upper cross tying and sign supporting element has the shape, in cross-section, of an inverted U, the outer surfaces of 65 which, at the ends, make close contact with

the inner surfaces of the tops of the slots in said members.

In testimony whereof I hereunto affix my signature.

ROBERT W. SCHWAB.
